SINTERING ORES AND THE LIKE

Anders Holmberg, Stockholm, Sweden

Application January 4, 1949, Serial No. 69,109

3 Claims. (Cl. 266—20)

1

The present invention relates to an apparatus for sintering ores, concentrate and other pulverulent materials of the kind comprising sintering pans, which are stationary during the sintering, and are portable after the sintering for emptying and charging. Known plants of this type are beset with certain drawbacks, viewed from the point of view of their operation, and have only restricted capacity.

The invention eliminates these drawbacks, and the characterizing feature of the plant is that a travelling crane or the like is arranged to bring each of the sintering pans to a roller device after the sintering of the material, and that the sintering pans after being placed on the roller device are started automatically and brought to a tilting device with automatic emptying, and are then, passed to one or more charging devices for automatic charging, and brought back to the place on the roller device for conveyance to the respective sintering positions.

In the accompanying drawings is diagrammatically shown an embodiment of a plant according to the present invention. Fig. 1 shows a longitudinal section of the plant, Fig. 2 a vertical section along the line I—I in Fig. 1, and Fig. 3 shows a vertical section along the line II—II in Fig. 1, and Fig. 4 shows a vertical section along the line III—III in Fig. 1.

Referring now to the drawings, the reference numeral 1 designates the sintering pans and A the sintering chamber. The pipes of each of the suction fans operating on the respective sintering pans are designated by 2. 3 designates a travelling crane arranged in the sintering chamber and running on a rail 9 with a stop 8. By this travelling crane 3 each sintering pan 1 is lifted and brought over the other sintering pans to a certain place 10a and set down on a roller device 11 in the charging chamber B. In order to obtain easy setting down of the pans in the pan stands and in the rolling device the travelling crane is provided with means for its handling with both a higher and a lower downwardly directed speed.

12, 13, 14 are charging bins provided with locking devices 4, 5, 6 for the materials to be charged, viz. bed material, mixed material and ignition breeze, each of said charging bins also being provided with charging rollers 15a, 15b, 15c. For reception of possible surplus material from the pans at the charging, an opening 7 is made in the charging floor. Said surplus material is collected and returned to the charging bin 13.

16 is a tipping frame for the pans which contain ready sintered material, said tipping frame

2

being rotary about two shafts. 17 designates a tipping stand located beneath the tipping frame 16 and provided with a bin and a sinter-crusher 18 having bars 19 through which the sintered material falls at the crushing. In order to obtain the quickest and most effective crushing of the sinter cake, the tooth wheels of the crusher 18 are so arranged that each wheel has one tooth 18a which is longer than the rest of the teeth. 10 Besides, the tooth wheels of the crusher are displaced along the shaft in such a manner that the longer teeth form a spiral along the crusher-shaft. The tops of the crusher teeth as well as the top side of the crusher bars 19 are provided 15 with a hard metal layer in order to prevent wear. Beneath the sinter crushed there is a bin with a screen 20, on which sinter bed material and unsintered, so-called return material, is separated from the finished sinter.

20 The finished crushed sinter in sizes from $\frac{3}{4}$ up to 6 inches passes over said screen out through the sluice 21 to be forwarded to a blast furnace or the like. The separated return material and sinter bed material is forwarded to the respective bins by means of a conveyor 22. The sinter bed material is loaded into the bin 12 and the return material is supplied to a return bin located in the raw material department.

Above the tipping stand 17 are exhausting 30 means, a dust hood 23 with shutter 24 for removing the dust resulting from the tipping.

The operation is as follows:

When a ready charged pan 1a is lifted from the roller device 11 at the place 10 by the 35 travelling crane 3, the limit switch 25 is released and the roller device 11 starts. The ready sintered pan 1b on the place 10a previously set down on the roller device 11 by the travelling crane 3 is, by means of the automatically started roller device 11, conveyed towards the tipping stand 17.

When the pan 1b has come within an appropriate distance from the tipping frame 16, limit switch 26 starting the mechanism for lifting the dust hood shutter 24 is actuated. If, contrary to 45 expectation, the dust hood shutter 24 should for some reason fail to open, a safety limit switch 27 will stop the roller device 11 before the pan can strike against the shutter.

When the pan 1b has entered the tipping 50 frame 16, it actuates a limit switch 28 and the roller device mechanism is stopped. A locking mechanism 29 is actuated together with the locking bars 30, which in turn lock the pan in the tipping frame 16 by means of a brake lift mechanism 38. Simultaneously the dust hood mecha-

nism is actuated and lowers the dust hood shutter 24 and closes the dust hood 23.

Immediately after the locking has been effected, the driving mechanism of the tipping frame 16 is actuated by means of a time relay, and the frame with the pan is rotated one or two revolutions, corresponding with the timing of the relay, the sintered material contained in the pan falling down in the bin of the tipping stand 17 for crushing and screening as mentioned above.

As soon as the pan has emptied its contents and returned to its horizontal position, the time relay unlocks the locking mechanism 29, the pan being released from the tipping frame 16.

The dust hood shutter 24 is also actuated by means of the time relay immediately after the release of the pan and is lifted at the same time as the rolling device 11 starts, carrying the pan 1b towards the charging devices 15a, 15b and 15c.

When the pan 1b has reached the limit switch 31, said switch is actuated and the charging device 15a for sinter bed material, which is charged on the fire base area in the pan, is started. During its continued advance the pan actuates the limit switch 32, which in turn actuates the charging device 15b for the mixed material, and thus the pan is charged with said material. When the pan has reached the limit switch 33 this, in turn, actuates the charging device 15c for ignition material which is intended to facilitate the ignition of the charges of the pans and which, if necessary, is applied to the surface of the charge. All charging devices are provided with time relays corresponding to an accurate filling of the pan in relation to its speed on the way.

When the pan 1b has reached the end position 10 on the roller device, it actuates a limit switch 34 which in turn stops the roller device, and the pan also actuates a limit switch 35 which prepares to start the roller device with a pan containing sintered material towards the tipping stand 17.

While the sintered pan 1b has been emptied and charged and has reached the end position in the place 10, the travelling crane 3 has brought the previously charged pan 1a to a sintering place 37 in the sintering chamber A and set it down in a pan stand 36. The pan is automatically connected to the suction pipe of the fan, is ignited, and then sintered the necessary time.

Immediately after having set down the pan 1a, the travelling crane 3 grips a ready sintered pan 1c and sets it down on the place 10a. Then the crane takes the ready charged pan 1b and brings it to its sintering place in the chamber, whereupon the process is repeated.

Having now described my invention, what I claim as new and desire to secure by Letters Patent is:

1. In sintering apparatus for sintering materials and for discharging the resulting sintered products, in combination: a plurality of portable sintering pans, said pans being stationary during sintering operations in a plurality of work positions, a roller table on which said pans are adapted to travel, said roller table being provided with automatic starting means, a plurality of suction pipes extending from said work positions, a pan tipping device for tipping said pans and discharging sintered material therefrom, a dust hood on said pan tipping device, said dust hood being provided with an opening therein to permit the passage of a sintering pan, and with means for automatically closing said opening after passage of said sintering pan therethrough, a crusher positioned adjacent said pan tipping device, said crusher being provided with crusher discs having teeth movable between parallel bars for crushing the sintered material, a travelling crane adapted to transport a pan containing sintered material from a work position to said roller table, said pan being then conveyed thereon to said pan tipping device, means for automatically discharging said sintered material from said pan at said pan tipping device, means for automatically returning said pan from which said sintered material has been discharged to one part of said roller table, means for automatically charging said returned pan with material to be sintered, and means for automatically returning said charged pan to another part of said roller table, whereby said charged pan may be transported by said travelling crane to a work position.

2. Sintering apparatus as defined in claim 1, wherein said tipping device includes means for automatically locking a sintering pan therein.

3. Sintering apparatus as defined in claim 1, wherein each crusher disc is provided with a plurality of teeth, one of which is longer than the other teeth of said disc.

ANDERS HOLMBERG.
